UNITED STATES PATENT OFFICE

2,035,607

PROCESS OF PURIFYING AND REFINING
HYDROCARBON OILSArthur Lachman, Berkeley, Calif., assignor to
Vapor Treating Processes, Inc., Los Angeles,
Calif., a corporation of California

Application July 26, 1929, Serial No. 381,305

19 Claims. (Cl. 196—35)

This invention relates to an improved process of purifying and refining hydrocarbon oils obtained by distillation or cracking of mineral oils such as lubricating oil stocks, lamp oil distillates, gasoline or naphtha stocks, or distillates derived from shale oil, and more specifically refers to the treatment of gasoline or naphtha stock produced by cracking crude petroleum oils or distillates derived from relatively high sulphur bearing mineral oils, in which hydrogen sulphide, mercaptans and other sulphur bearing compounds, as well as varying percentages of oxygenated hydrocarbons and unstable hydrocarbons (such as diolefines and acetylenes) may be present or formed during said distillation or cracking operation.

Reference is made to United States Patent No. 1,809,170, granted June 9, 1931 to Arthur Lachman, Serial No. 361,513, filed May 8, 1929 for Process of refining hydrocarbon oils, which discloses a vapor phase method or process for purifying and refining mineral oil products with a water solution of certain metallic salts, or mixtures of the same, such as zinc, copper, cadmium, mercury iron, chromium, manganese, aluminum, nickel or cobalt water soluble salts which may be the chloride, bromide, iodide, sulphate, sulphite, nitrate and also any of the water soluble salts of the above named metals or organic acids, such as the sulphonic acids of benzol, toluol and xylol, or the sulphonnic acids derived from the treatment of petroleum oil with sulphuric acid, it being observed that the enumerated metals may be classed as "heavy metals" and it being understood further that the word "heavy" as used in the term "salt of a heavy metal" (which latter phrase is embodied in the claims to comprehend the materials capable of use in my process) is to be understood as including those metals which form soluble salt solutions capable of being maintained in solution at the temperatures and pressures at which the hereinbefore-described process may be practiced.

For the purpose of simplifying the description of my invention, reference will be made mainly to gasoline stock. Crude gasoline stocks obtained by distillation or cracking petroleum oils, consists of a mixture of saturated and unsaturated hydrocarbons together with sulphur compounds, nitrogen bases and other substances of an undefined nature. These latter substances are readily oxidizable at ordinary temperature and are usually responsible for the change of color which takes places when refined gasoline is stored. These oxidizable substances are removed with

difficulty when gasoline stocks are treated by the methods known in the art.

By well-known methods, crude gasoline stocks obtained by distillation of crude petroleum oil or by cracking a higher boiling petroleum oil, are customarily treated with approximately from 1 per cent to as high as 8 per cent or higher by weight, sulphuric acid, the quantity of sulphuric acid depending upon the nature of the gasoline stock to be treated and the degree of refinement desired. This acid treatment usually consists in commingling the gasoline stock with the required amount of sulphuric acid necessary to obtain the desired extraction, either by the well-known batch or continuous treatment, after which the products of the acid reaction are permitted to settle and are then withdrawn from the treated gasoline stock. The acid treated gasoline stock is then neutralized by washing with a water solution of an alkali and finally with water. This treatment removes most of the impurities, but subsequent treatments are usually necessary to deodorize and remove or convert corrosive sulphur compounds into noncorrosive bodies. For this purpose, a water solution of sodium plumbite or sodium hypochlorite is usually employed to render the gasoline stock "sweet" to the "doctor test". In these treatments, particularly where hypochlorite of soda is employed, chlorinated hydrocarbons may be formed to a small extent which may be converted into corrosive compounds during a subsequent distillation.

The general objections to a treatment of this character, are as follows: (1) Gasoline purified by this method frequently becomes discolored when stored for a period of time; (2) considerable quantities of sulphuric acid are required, which are difficult to recover; (3) as high as 10 per cent of the valuable unstable hydrocarbons contained in the gasoline stock may be lost and (4) the treatment must frequently be followed by a sweetening process, such as that heretofore described.

Now, I have discovered that the sulphuric acid normally used to treat crude gasoline stocks may be reduced to a great extent, and in many cases may be entirely eliminated by the employment of a water solution of certain metallic salts, or mixtures of the same which may be zinc, copper, cadmium, mercury, iron, chromium, manganese, aluminum, nickel or cobalt water soluble salts such as the chloride, bromide, iodide, sulphate, sulphite, nitrate, nitrite, and also any of the water soluble salts of the above named metals.

of organic acids, such as the sulphonic acids of benzol, toluol and xylol, or the sulphonic acid salts derived from the treatment of petroleum oils with sulphuric acid.

The process described briefly consists in passing the hydrocarbon oil product, such as gasoline stock, in a liquid phase, commingled with a substantially concentrated water solution of any of the above named salts or mixtures thereof, through a heating coil under a pressure sufficient to prevent any substantial vaporization therein, at temperatures of approximately 300 to 600 degrees F., and then immediately releasing the pressure and separating by distillation the purified hydrocarbon oil product from the water solution of the metallic salt or salts, the extracted impurities and products of polymerization or condensation, or as shown in Figure II the gasoline stock and water solution of metallic salt or salts may be first separately heated and then commingled under a pressure.

The hydrocarbon oil stock to be treated by my invention may or may not have had a preliminary treatment with sulphuric acid, or other agents to partly purify the same, or may be first partly purified by my invention and the purification completed by methods known in the art such as treatment with caustic alkali, sulphuric acid, etc. In the case of gasoline stocks produced by cracking high sulphur bearing crude petroleum oil or residuum, it may be advantageous to treat such gasoline stocks with sulphuric acid or sulphuric anhydride at low temperatures, ranging from approximately 0 to 30 degrees F. before the treatment with a concentrated water solution of any of the aforesaid water soluble metallic salts at the elevated temperatures and pressures heretofore stated and this treatment may also be followed by treatment with an alkaline water solution of sodium, potassium, or calcium hydroxide, or the carbonates of sodium or potassium.

Although a solution of less concentration may be employed which may range from 50 or less to approximately 85 per cent, the strength of the water solution of the metallic salt or mixtures of salts employed is preferably a substantially concentrated solution, and the temperature employed for the treatment is preferably approximately 300 to 600 degrees F., this temperature depending upon the vaporizing temperature of the oil under treatment.

One of the principal objects of this invention is to accomplish a purification of gasoline or naphtha stocks produced by thermo molecular decomposition of high boiling petroleum oils, by a treatment with a substantially concentrated water solution of a metal salt under a pressure sufficient to prevent any substantial vaporization thereof and at a temperature of approximately 300 to 600 degrees F., followed by a distillation and fractionation operation to separate the products of reaction and higher boiling polymerized products from the purified gasoline or naphtha stocks.

Another object of the invention is to provide a continuous, rapid and economical process for purifying gasoline stocks produced by the thermo decomposition of higher boiling petroleum oils, by treating the same under super-atmospheric pressure sufficient to maintain a liquid phase, with a substantially concentrated water solution of a metallic salt at temperatures of approximately 300 to 600 degrees F., to polymerize substantially all the unstable hydrocarbons con-

tained therein and at the same time remove oxygenated hydrocarbons and render the gasoline "sweet" to the "doctor test".

Another object of the invention is to provide a continuous, economical method for improving the color and removing gums and gum forming material from gasoline or naphtha stock so that the same may be kept in storage for relatively long periods of time without changing color or quality by the formation of polymerized bodies. 10

Various other objects and advantages of the present invention will be apparent from the description of the preferred form or example of the process embodying the invention. For this purpose, reference is made to the accompanying 15 drawings in which there is illustrated two forms of apparatus in which the invention may be performed.

Figure I represents one form of an apparatus for carrying out the invention in which the petroleum oil product to be treated is first commingled with the water solution of a metallic salt and thereafter heated to a reaction temperature by causing the same to pass through a heating coil under pressure. 20

Figure II represents another form of apparatus in which the petroleum oil product and the water solution of a metallic salt are separately heated to a reaction temperature and are thereafter commingled by means of a jet mixer. 30

In Figure I, 3 represents generally a tank for holding a supply of gasoline or other petroleum oil stock to be processed. Pipe 1, controlled by valve 2, connects the gasoline stock tank 3 near the top to a source of supply not shown. Pipe 4, controlled by valve 5, connects the gasoline stock tank 3 to the inlet side of pump 6. Pipe 40, controlled by valve 41 connects pipe 4 to a fractionating tower not shown. Pipe 7 connects pump 6 to jet mixer 8. 13 represents generally a tank for holding a concentrated water solution of a metallic salt such as zinc chloride, zinc bromide, zinc iodide, etc., or any of the other metal salts heretofore enumerated. Pipe 14, controlled by valve 15, connects tank 13 near the top to a source of supply not shown. Pipe 11, controlled by valve 12, connects tank 13 near the bottom to the inlet side of pump 10. Pipe 9 connects the discharge side of pump 10 to jet mixer 8. Pipe 16 connects the jet mixer 8 to heater coil 38. The heater coil 38 is stationed in the furnace 17. The furnace 11 is provided with a burner 18 which leads to a supply of fuel not shown. Pipe 39, controlled by pressure release valve 19, connects the heater coil 38 to distillation tower 20. The distillation tower 20 is provided with bubble trays 21. Pipe 22, controlled by valve 23, connects the distillation tower 20 near the bottom to a source of water supply not shown. Pipe 25 controlled by valve 24, connects distillation tower 20 at the bottom to tank 26. Pipe 28 controlled by valve 27, connects the tank 26 to a storage not shown. The pipe 29 connects distillation tower 20 at the top to condenser coil 31. Condenser coil 31 is stationed in the condenser box 30 and is provided with a water inlet pipe 32 and a water outlet pipe 37. The pipe 32 leads to a source of water supply not shown and the water outlet pipe 37 leads to a waste receiver not shown. Pipe 33 connects condenser coil 31 to treated gasoline tank 34. Pipe 36, controlled by valve 35, connects the treated gasoline tank near the bottom to a storage not shown. 50

In Figure II, 3 represents generally a tank for

holding a supply of gasoline or other petroleum oil stock to be processed. Pipe 1, controlled by valve 2, connects the gasoline stock tank 3 near the top to a source of supply not shown. Pipe 4, controlled by valve 5, connects the gasoline stock tank 3 to the inlet side of pump 6. Pipe 40, controlled by valve 41, connects pipe 4 to a fractionating tower not shown. Pipe 7 connects pump 6 to heater coil 38. Heater coil 38 is stationed in a furnace 17. Furnace 17 is provided with a burner 18 which leads to a fuel supply not shown. 13 represents generally a tank for holding a concentrated water solution of a metallic salt such as zinc chloride, zinc bromide, zinc iodide, etc., or 15 any of the other metallic salts heretofore enumerated. Pipe 14, controlled by valve 15, connects tank 13 near the top to a source of supply not shown. Pipe 11 controlled by valve 12, connects tank 13 near the bottom to the inlet side 20 of pump 10. Pipe 9 connects the discharge side of pump 10 to heater coil 44. Heater coil 44 is stationed in furnace 42. Furnace 42 is provided with a burner 43 which leads to a fuel supply not shown. Pipe 45 connects heater coil 44 to jet 25 mixer 8. Pipe 39 connects heater coil 38 to jet mixer 8. Pipe 16 connects jet mixer 8 to reaction chamber 46. Pipe 47 controlled by pressure release valve 19, connects reaction chamber 46 to distillation tower 20. Distillation tower 20 is 30 provided with bubble trays 21. Pipe 22, controlled by valve 23, connects distillation tower 20 to a source of water supply not shown. Pipe 25, controlled by valve 24, connects the bottom of distillation tower 20 to tank 26. Pipe 28, controlled by valve 27, connects tank 26 to a storage 35 not shown. Pipe 29 connects distillation tower 20 at the top to condenser coil 31. Condenser coil 31 is situated in the condenser box 30, and is provided with a water inlet pipe 32 and a water outlet pipe 37. The pipe 32 leads to a source of water supply not shown and the water outlet pipe 37 leads to a waste receiver not shown. Pipe 33 connects the condenser box 30 to treated gasoline tank 34. Pipe 36, controlled by valve 35, connects 40 the treated gasoline tank 34 near the bottom to a storage not shown.

The process as carried out in the apparatus described in Figure I, is as follows:

Tank 3 is filled with the petroleum oil product 50 to be treated by operation of valve 2. Petroleum oil distillate, such as gasoline stock contained in tank 3, is permitted to flow through pipe 4 and into the inlet side of pump 6, the rate of flow being governed by operation of valve 5. Pump 6 continuously discharges the gasoline stock under a pressure of approximately 100 to 1000 pounds gauge, into jet mixer 8, wherein the gasoline stock is continuously commingled with the necessary quantity of a substantially concentrated water solution of a metallic salt such as 55 zinc chloride from the supply tank 13.

The water solution of metallic salt contained in the supply tank 13 is permitted to flow through pipe 11 and into the inlet side of pump 10 which 60 discharges the same under a pressure ranging from approximately 100 to 1000 pounds gauge through pipe 9 and into said jet mixer 8, the rate of flow being governed by operation of valve 12.

The quantity of water solution of metallic salt 65 may range from as low as 1 per cent to as high as 10 per cent or higher, by volume, depending upon the stock to be treated. For example, if a crude gasoline stock contains a high percentage of impurities to be extracted as high as 10 per 70 cent by volume or more of a concentrated water

solution of any of the aforesaid metallic salts or mixtures of the same may be employed. The pressure maintained on the system by means of pumps 6 and 10 is so regulated that the commingled mixture of the water solution of metallic 5 salt or salts and gasoline stock under treatment passing through heater coil 38 will be maintained in a substantially liquid phase, such pressure depending upon the boiling point of the gasoline stock and the temperature employed. From jet 10 mixer 8, the gasoline stock, commingled with the water solution of the metallic salt or salts passes through heater coil 38, pipe 39 and pressure release valve 19, where the pressure is reduced to atmospheric or approximately atmospheric, and 15 then passes into distillation tower 20. The commingled mixture passing through heater coil 38 is heated to the reaction temperature. Preferably a temperature ranging from approximately 300 to 400 degrees F. is suitable to employ in treating ordinary gasoline stocks. However, with some 20 grades of petroleum oil distillates, as high as 600 degrees F. or a little higher, may be employed.

In distillation tower 20, the purified gasoline stock at a temperature ranging from approximately 300 to 400 degrees F., together with a portion of the water content of the salt solution, are vaporized and separated from the products of the reaction and the metallic salt or salts employed. The purified gasoline stock, mixed with 25 water vapor, passes out of distillation tower 20, through pipe 29, into condenser coil 31, stationed in the condenser box 30, wherein the said purified gasoline stock and water vapor are condensed to a liquid, passing through pipe 33 and 30 into the treated gasoline tank 34. A cooling fluid such as water is employed to condense the gasoline vapors passing through condenser coil 31 coming from a source not shown through pipe 32 and passing out of condenser box 30 through 35 pipe 37. From the treated gasoline tank 34 the purified gasoline stock may be conducted to a storage not shown, through pipe 36, controlled by valve 35. The purified gasoline stock so obtained 40 may be thereafter treated, if necessary, by other methods known in the art, or may be subjected to a distillation operation to separate fractions having any desired range of boiling points.

The metallic salts and products of reaction 45 which separate in the bottom of distillation tower 20 are intermittently or continuously drawn into tank 26 through pipe 25, the flow being controlled by valve 24, water being continuously or intermittently introduced into the lower section of distillation tower 20, through pipe 22, controlled by 50 valve 23, in quantities sufficient to replace the vaporized water from the metallic salt water solution so as to maintain the used metallic salts or compounds and products of the reaction in a 55 fluid condition.

From tank 26 the excess water solution of metallic salt or salts and products of the reaction are conducted to a storage not shown through pipe 29, controlled by valve 21, and the metallic salts 60 or compounds are separated from the reaction products and purified for re-use.

As illustrated in Figures I and II, if it is desired to treat a gasoline stock coming directly from a fractionating tower, or other distillation 65 apparatus, in a vapor or semi-vapor state, valve 5 is closed and valve 41 is opened, which permits the gasoline stock coming from a source not shown, in a vapor or semi-vapor state, to flow through the pipe 40 and into the inlet side of 70 75

pump 6, wherein the gasoline stock is completely condensed to a liquid by the applied pressure maintained on the system and the introduction of the cool water solution of a metallic salt or salts in Figure I and by the application of pressure in Figure II.

The process as carried out in the apparatus described in Figure II is substantially the same as the process heretofore described for Figure I, except that the petroleum oil or gasoline stock to be treated and the water solution of a metallic salt or salts are first separately heated to the reaction temperature by heating coils 38 and 44 at a pressure sufficient to prevent any substantial vaporization therein, after which the heated gasoline stock and heated water solution of a metallic salt or salts as heretofore enumerated are commingled in jet mixer 8 and pass through pipe 16, reaction chamber 46, pipe 47, pressure release valve 19 and into distillation tower 20.

While the process herein described is well adapted for carrying out the objects of the present invention, it is to be understood that various modifications and changes may be made without departing from the invention, such for example, as the use of centrifugal or other mechanical mixers, or the employment of any of the well-known contact towers wherein a water solution of a metallic salt or mixtures of metallic salts, either organic or inorganic, heretofore enumerated, may be commingled with or brought into contact with a petroleum oil at a pressure sufficient to prevent substantial vaporization at the reacting temperature, and the invention includes all such modifications and changes as come within the scope of the appended claims.

What I claim is:

1. A process of purifying petroleum oil products, comprising, commingling a petroleum oil product with a substantially concentrated water solution of a zinc salt, passing the commingled mixture through a heating coil and heating the mixture to a reaction temperature under pressure sufficient to prevent substantial vaporization, releasing the pressure and separating by vaporization, fractionation and condensation a purified petroleum oil product from products of reaction and excess treating agent.

2. A process of purifying petroleum oil products, comprising, commingling a petroleum oil product with a substantially concentrated water solution of a zinc salt, passing the commingled mixture through a heating coil and heating the mixture to a temperature of approximately 300 to 600 degrees F. under pressure sufficient to prevent substantial vaporization, releasing the pressure and separating by vaporization, fractionation and condensation a purified petroleum oil product from products of reaction and excess treating agent.

3. A continuous process for purifying gasoline stocks, comprising, continuously commingling gasoline stock with a substantially concentrated water solution of a zinc salt, continuously passing the commingled mixture through a heating element and heating the mixture to a temperature of approximately 300 to 600 degrees F., under a pressure sufficient to prevent substantial vaporization, releasing the pressure and separating by vaporization, fractionation and condensation a purified gasoline stock from products of reaction and excess treating agent.

4. A process of removing gum forming constituents from cracked gasoline stock, comprising, commingling a cracked gasoline stock with

a water solution of a zinc salt and heating the commingled mixture to a temperature of approximately 300 to 600 degrees F., under a pressure sufficient to prevent substantial vaporization, while passing through a heating coil, for a period of time sufficient to cause the unstable hydrocarbons contained in the cracked gasoline stock to polymerize with the formation of gums, then reducing the pressure to approximately atmospheric and separating by vaporization, fractionation and condensation a purified gasoline stock from products of reaction, polymerization and excess treating agent.

5. A continuous process for purifying gasoline stocks derived by thermo-decomposition of higher boiling petroleum oils, comprising, continuously commingling gasoline stock with a water solution of zinc sulphate, continuously passing the commingled mixture through a heating coil and heating the commingled gasoline stock and water solution of zinc sulphate to a temperature of approximately 300 to 400 degrees F., under a pressure sufficient to prevent substantial vaporization, continuously releasing the pressure after the commingled mixture of gasoline stock and water solution of zinc sulphate has passed through said heating coil, continuously passing the treated gasoline stock, products of reaction and excess treating agent into a vaporizing tower, continuously vaporizing, fractionating and separating a purified gasoline stock and water vapor from higher boiling reaction products and excess treating agent.

6. A continuous process of purifying gasoline stocks derived by the thermo molecular decomposition of higher boiling petroleum oils, comprising, continuously commingling gasoline stock with a water solution of a zinc salt, continuously passing the commingled mixture through a heating coil and heating the commingled gasoline stock and water solution of zinc salt to a temperature of approximately 300 to 400 degrees F., under a pressure sufficient to prevent substantial vaporization, continuously releasing the pressure and continuously passing the heated mixture of gasoline stock, water solution of zinc salt and products of reaction into a vaporizing tower, continuously vaporizing and separating by vaporization, fractionation and condensation a purified gasoline stock mixed with water from higher boiling products of reaction and excess treating agent, continuously introducing water into the vaporizing tower in quantities sufficient to replace the water of vaporization, continuously withdrawing products of reaction and introduced water containing excess treating agent, substantially as described.

7. A process of purifying gasoline stock, comprising, contacting gasoline stock with a water solution of a zinc salt while passing through a heating coil, under a pressure sufficient to prevent any substantial vaporization, and heating the mixed gasoline stock and water solution of zinc salt to a temperature of approximately 300 to 400 degrees F., releasing the pressure after the gasoline stock mixed with the water solution of zinc salt has passed through the heating coil, and separating by vaporization, fractionation and condensation a purified gasoline stock from higher boiling products of reaction and excess treating agent.

8. A process of purifying petroleum oil, comprising, commingling the petroleum oil with a water solution of zinc salt, passing the commingled mixture through a heating coil and

heating the commingled mixture to a reaction temperature, under a pressure sufficient to prevent substantial vaporization, releasing the pressure and passing the treated petroleum oil, products of reaction and water solution of zinc salt into a vaporizing tower, maintaining the zinc salt in a fluid condition by addition of water, vaporizing, fractionating and separating a purified petroleum oil, mixed with water vapor, from higher boiling reaction products and excess treating agent.

9. A process of purifying petroleum oil products, comprising, commingling a petroleum oil product with a substantially concentrated water solution of a zinc salt, passing the commingled mixture through a heating coil and heating the mixture to a temperature of approximately 400 degrees F. under pressure sufficient to prevent substantial vaporization, releasing the pressure and separating by vaporization, fractionation and condensation a purified petroleum oil product from products of reaction and excess treating agent.

10. A continuous process for purifying gasoline stocks, comprising, continuously commingling gasoline stock with a substantially concentrated water solution of a zinc salt, continuously passing the commingled mixture through a heating element and heating the mixture to a temperature of approximately 400 degrees F., under a pressure sufficient to prevent substantial vaporization, releasing the pressure and separating by vaporization, fractionation and condensation a purified gasoline stock from products of reaction and excess treating agent.

11. A process of purifying gasoline stock, comprising, contacting gasoline stock with a water solution of a zinc salt while passing through a heating coil, under a pressure sufficient to prevent any substantial vaporization, and heating the mixed gasoline stock and water solution of zinc salt to a temperature of approximately 400 degrees F., releasing the pressure after the gasoline stock mixed with the water solution of zinc salt has passed through the heating coil, and separating by vaporization, fractionation and condensation a purified gasoline stock from higher boiling products of reaction and excess treating agent.

12. A process of purifying petroleum oil products, comprising, commingling a petroleum oil product with a water solution of a salt of a heavy metal, passing the commingled mixture through a heating coil and heating the mixture to a reaction temperature under pressure sufficient to prevent substantial vaporization, releasing the pressure and separating by vaporization, fractionation and condensation a purified petroleum oil product from products of reaction and excess treating agent.

13. A process of purifying gasoline stock, comprising, contacting gasoline stock with a water solution of a salt of a heavy metal while passing through a heating coil, under a pressure sufficient to prevent any substantial vaporization, the gasoline stock and water solution of the metal salt being heated to a temperature of approximately 400° F., releasing the pressure after the gasoline stock mixed with the water solution has passed through the heating coil, and separating by vaporization, fractionation and condensation a purified gasoline stock from higher boiling products of reaction and excess treating agent.

14. A process of purifying a petroleum oil product comprising heating said product and a substantially concentrated solution of the salt of a heavy metal under a pressure sufficient to prevent substantial vaporization and at a reaction temperature and,—after the same have been commingled under said pressure,—reducing the pressure and separating by vaporization, fractionation and condensation a purified oil product from products of reaction and the excess treating agent.

15. The process of purifying petroleum oil products comprising passing the oil through a heating zone and maintaining the oil under pressure sufficient to prevent substantial vaporization while heating the oil to a temperature somewhere between 300° to 600° F., forcing into the stream of oil a substantially concentrated water solution of a heavy metal salt, maintaining pressure on the mixture of oil and water solution of the salt after they are mixed, reducing the pressure and passing the mixture to a collecting zone, and fractionating the purified oil.

16. A process of purifying a petroleum oil product which comprises causing said product to vaporize from a heated commingled mixture of the product and a water solution of a zinc salt by reducing the pressure on said heated mixture.

17. A process of purifying a petroleum oil product which comprises causing said product to vaporize from a heated commingled mixture of the product and a water solution of an iron salt by reducing the pressure on said heated mixture.

18. A process of purifying a petroleum oil product which comprises causing said product to vaporize from a heated commingled mixture of the product and a water solution of a cadmium salt by reducing the pressure on said heated mixture.

19. The method of purifying a hydrocarbon initially available in a vapor or semi-vapor phase which comprises condensing said hydrocarbon by imposition of pressure thereupon and by commingling a cool aqueous solution of a salt of a heavy metal therewith, maintaining a pressure thereupon while the mixture is heated to prevent substantial vaporization thereof, and finally reducing the pressure to vaporize said mixture.

ARTHUR LACHMAN. 60
